BURNER CONTROL VALVE

John H. Thornberry, Whitefish Bay, Wis., assignor
to Milwaukee Gas Specialty Company, Milwaukee, Wis., a corporation of Wisconsin

Application April 20, 1950, Serial No. 157,130

13 Claims. (Cl. 236—80)

1

This invention relates to burner control valves, and is particularly concerned with an improved control and safety shut-off valve of the type which, under the control of fluid pressure and thermoelectric power, controls the flow of gaseous fuel to a main burner and to a pilot burner therefor.

While I shall hereinafter, in connection with the drawings, describe one particular control valve embodying the present invention in relation to one particular burner system, it is to be understood that this invention is not in its broader aspects limited to the particular embodiment selected for illustration, nor to use in the particular burner system shown and described.

In prior control systems of the type with which this invention is concerned there has been interposed in the fuel supply pipe leading to the main burner a diaphragm valve under the control of a thermoelectric generator positioned to be heated by the pilot burner for the main burner in conjunction with another valve also in the fuel supply pipe leading to the main burner and which is operable to shut off the supply of fuel to both the main burner and the pilot burner when the pilot burner is extinguished. In these prior systems the control of the diaphragm valve by the thermoelectric generator has been obtained by a pilot valve under control of an electromagnet connected in circuit with the thermoelectric generator and operable between one position in which fuel pressure is imposed on the diaphragm valve to close the same and another position in which the fuel is vented from the diaphragm chamber, for example, into the furnace or into proximity to the pilot burner.

In order to prevent bleeding or venting of the gas through the vent when the diaphragm valve is closed, certain of the above mentioned prior schemes employ aligned jets, one opening into the chamber wherein the fuel pressure is imposed to close the diaphragm valve, with the other opening from the chamber through the vent, and the pilot valve being operable between one position closing the inlet jet and its other position closing the outlet jet. These schemes thus entail control of both an inlet port opening into the diaphragm chamber and an outlet port opening therefrom; also a vent tube leading from the diaphragm chamber into the furnace or into proximity to the pilot burner in addition to the fuel supply pipe for the pilot burner, and separate valve structures one for the main or diaphragm valve and the other for the safety shut-off valve.

2

One of the main objects of the present invention is to provide an improved automatically operable control valve for the control of the gas supply to a burner by utilizing energy of the gas as a source of power to operate the valve and wherein the application of the energy of the gas for operating the valve is under the control of a thermoelectric generator positioned to be heated by the pilot burner.

Another object of the invention is to provide a valve of the class described wherein all necessary elements are combined into one compact unit to simplify installation and service.

Another object of the invention is to provide a valve of the class described which does not require control of both inlet and outlet ports for the diaphragm chamber, or a separate vent tube leading from the diaphragm chamber into the furnace or into proximity to the pilot burner.

Another object of the invention is to provide means for preventing opening of the main valve while the pilot burner is being lighted; more particularly, latch means for latching in open position during resetting, or lighting of the pilot burner, a valve which controls the application of fuel energy to the main valve to close the same.

Another object of the invention is to provide a device that will fail safe under all conditions and which will provide 100% safety shut-off of the main burner, the pilot burner, and the bleed or vent gas.

Another object of the invention is to provide for safety shut-off in case the pilot burner becomes extinguished for any reason.

Another object of the invention is to provide a device in which bleed gas from the main valve is utilized as the gas for the pilot burner.

Another object of the invention is to provide for safe lighting, and, more particularly, a high speed actuating mechanism for assuring that the main valve will be urged against and held to its seat to shut off the supply of fuel to the main burner during resetting or cocking the shut-off valve for the pilot burner and igniting the pilot burner.

Another object of the invention is to make the valve suitable or quickly convertible for use with different gases, such as manufactured gas, natural gas, butane, propane, or other gases.

Further objects and advantages of the invention will appear from the following detailed description, taken in connection with the accompanying drawings which show the construction and operation of an illustrative embodiment of the invention and one manner of using the

device according to the invention in a burner system.

In the drawings:

Figure 1 is a diagrammatic view showing more or less schematically the basic elements of the burner control valve of the present invention embodied in an illustrative form of burner system;

Figure 2 is an elevational view of the outer end of the control valve, with the cover removed, partially in section and schematic in part;

Figure 3 is a sectional view, partially in elevation, taken, in general, along the line 3—3 of Figure 2;

Figure 4 is a sectional view, partially in elevation, taken, in general, along the line 4—4 of 15 Figure 2;

Figure 5 is an axial sectional view through one of the valve body parts of the valve shown in Figures 2, 3, and 4, and showing fragmentarily and in section a portion of the other valve body 20 part;

Figure 6 is a side elevational view of one illustrative form of power unit assembly suitable for use with the present invention;

Figure 7 is an end view of the power unit assembly looking from the left hand end of Figure 6; and

Figure 8 is a diagrammatic view similar to Figure 1 but showing, in addition, mechanism for assuring safe lighting.

Referring now to the drawings, and first to Figure 1 which shows more or less schematically the basic elements of the invention laid out in diagrammatic manner to facilitate understanding the invention, the burner shown at 1 is the main burner. It may be the main burner, for example, for a room or space heater, or it may be the main burner for a water heater, or for a floor furnace, an oven burner, or any other burner, and of suitable construction.

A fuel supply pipe or conduit 2 leads to the burner 1 for the delivery of gaseous or other fuel thereto, for example, through a mixing chamber 3 to which air is admitted through adjustable air inlets (not shown), as well understood in the art. The flow of gas through the conduit 2 is controlled by a main valve 4 shown in the form of a diaphragm valve.

The diaphragm valve 4 is shown in Figure 1 as comprising a pair of valve body parts 5 and 6. The valve body part 6 has a gas inlet 7, a gas outlet 8, and a valve seat 9 between inlet 7 and outlet 8. Contiguous sections of conduit 2 are connected to inlet 7 and outlet 8. A diaphragm 10 is secured marginally between the valve body parts 5 and 6, and separates the flow of fuel through inlet 7 and outlet 8 from the diaphragm chamber 11 on the opposite side of the diaphragm. The diaphragm 10 carries a main valve member 12 which is adapted to seat upon the valve seat 9 to shut off the flow of fuel to the main burner 1, and for movement to position away from said seat for flow of fuel to the burner 1.

The valve 4 has first passage means indicated in Figure 1 at 13, 14, and 15 for receiving fuel from the inlet side of the valve and applying the pressure or energy thereof into diaphragm chamber 11 and thereby to diaphragm 10 to close the valve member 12. The valve 4 also has second passage means, indicated in Figure 1 at 13, 16, and 15, which also receives fuel from the inlet side of the valve and applies the pressure or energy thereof into chamber 11 and thereby to diaphragm 10 to close valve member 12. The leg

14 of the first passage means has a relatively restricted orifice 17 which diminishes the supply of gas to the diaphragm chamber 11 through the first passage means 13, 14 and 15 to less than that which is supplied to the diaphragm chamber 11 through the second passage means 13, 16, and 15. The leg 13 of the first and second passage means preferably has a suitable filter 18 therein.

A bleed or vent conduit 19 connected, for example, as shown schematically in Figure 1, thus leads from both the first passage means 13, 14 and 15, and the second passage means 13, 16, and 15 for supplying gas therefrom as will presently appear. The conduit 19 leads to a pilot burner 20 and supplies the pilot burner supply of fuel to the pilot burner 20 which is located in juxtaposition to the main burner 1 to maintain a pilot flame for igniting the main burner. The pilot burner 20 may be in the form shown and described in the copending application of Eugene E. Meusy, Serial No. 146,686, filed February 28, 1950, or in copending application of Stephen L. Kile, Serial No. 693,927, filed August 30, 1946, now abandoned, or in the copending application of Charles E. Hajny, Serial No. 39,339, filed July 17, 1948, or of any other form.

Suffice it to state that the pilot burner 20 has one or more orifices at 21 for maintaining one or more flames for igniting the main burner 1 and for heating the one or more hot junctions 30 of a thermoelectric generator 22 which may be in the form of a thermocouple of concentric or other form, or in the form of a thermopile. The pilot burner 20 preferably has a relatively restricted orifice at 23 which matches or is of the same size 35 as the relatively restricted orifice 17 in the leg 14 of the first passage means of the valve.

The flow of gas through the second passage means, for example, through the leg 16 thereof is 40 controlled by a thermoelectric valve which is indicated, in general, at 24 in Figure 1, and acts as an automatic valve under the control of a thermostat or other condition responsive control indicated at 25. While the valve 24 may be of 45 any other suitable form within the broader aspects of the present invention, one suitable form which the valve 24 may take is illustrated in Figures 2, 4, 6, and 7.

As shown in Figures 2, 4, 6, and 7, the valve 24 50 comprises an armature 26 pivoted on needle pivots 27 carried by a pivot bracket 28. The armature 26 is provided with an actuating coil 29 which, when energized by the heating of the hot junction means of the thermoelectric generator 22 by the heat of the pilot burner flame, moves the armature 26 to attracted position against the end of a nozzle 30 to shut off the flow of fuel through the second passage means 13, 16, and 15. When the coil 29 is deenergized, for example, by extinguishment of the pilot burner flame, or by opening of the thermoelectric circuit therefor by the thermostat 25 or other condition responsive device, a spring 31 moves the armature to retracted position and away from the nozzle 30 for the flow of gas through the second passage means 13, 16, and 15. The coil 29 has a core or coil spool 32 which with the coil constitutes the actuating electromagnet for the automatic valve 24.

In the form of automatic valve shown in Figures 2-5, the nozzle 30 is mounted in and opens 70 inwardly through the wall of diaphragm chamber 11. The nozzle 30 may be secured in place by a nut 34, and may be provided with a washer 35. As shown in Figures 2 and 3, an opening or pas-

sage 36 opens from the valve inlet 7. Control and pilot gas enters passage 36 and passes through filter 18. Outwardly of filter 18 one part of the gas enters passage 37 which leads to the nozzle or valve orifice 38. A pipe plug may be provided at 39. The other part of the gas enters a passage 40 and orifice 41 which leads through a valve plug 42, rotatably mounted in the valve body part 5, to the chamber 11 on the outer side of diaphragm 10. A filter cap is provided at 43.

When nozzle 30 is open, gas will pass to chamber 11 through port 44 and also along a square or polygonal pin 45 which operates in a passage 46 of circular section opening into the interior of an obliquely disposed tubular body part 47. A safety shut-off valve member 48 is adapted to seat, for example, upon a valve seat 49 at the inner end of tubular part 47 to shut off the supply of gas to the pilot burner 20. The vent, bleed or gas supply conduit 19, from which the pilot burner 20 receives gas, is connected to the pilot outlet 50 of the safety shut-off valve as shown in Figure 2.

An electromagnet 51 having a magnet frame 52 and a coil 53 is adapted for holding an armature 54 connected at 55 to valve member 48 in attracted position and thereby the valve 48 open when the thermoelectric generator 22 is heated by the pilot burner flame. The electromagnet 51 is connected in circuit with the thermoelectric generator by lead conductors 56 and 57 (Figure 1) which may be of coaxial form as shown in Oscar J. Leins Patent No. 2,126,564, issued August 9, 1938, or of other suitable form. Circuit connector means is shown at 58 in Figure 2 for connection with the electromagnet 51 and with the lead conductors of coaxial form, but, of course, this may vary. When the pilot burner 20 is extinguished the electromagnet 51 ceases to hold valve 48 open, and this valve moves to closed position, for example, under the action of a spring 59 to shut off the supply of fuel to the pilot burner 20 and thereby the bleeding or venting of fuel from the first and second passage means 13, 14 and 15 and 13, 16, and 15 respectively, as shown in Figure 1.

A reset button 60 (Figures 1 and 2) is adapted to be pressed inwardly to cause its stem 61 to engage and move valve 48 to open position with accompanying movement of armature 54 to attracted position and to hold armature 54 in attracted position until the pilot burner 20 is ignited and heats the thermoelectric generator 22 sufficiently to retain armature 54 in attracted position and valve 48 open. When reset button 60 is released, it may be actuated to its outwardly projected position, for example, by a coiled spring 62.

For the purpose of holding the valve constituting armature 26 of the automatic valve 24 open so that energy will be applied to hold the main valve 12 closed while resetting the armature 54 of the safety shut-off valve 48 to attracted position, means is provided, for example, in the form of latch means. This latch means comprises a spring 63 mounted in place at 64 (Figure 2). One end of the spring 63 may bear against the valve body part 5 at 65. The other arm of the spring 63 engages the armature 26 of the automatic valve at 66. The spring 63 extends across the path of travel of the inner end of the pin 45. The outer end of the pin 45 cooperates with a tapered portion 67 on the reset stem 61.

When reset button 60 is pressed inwardly, the tapered portion 67 thereof engages the outer end of the pin 45 and moves this pin inwardly or away

from the axis of the reset stem 61. In this movement the inner end of pin 45 engages the arm of the spring 63 and moves the same in a direction to force the armature 54 away from the nozzle 30, thus opening the automatic valve. This assures the passage of sufficient gas to diaphragm chamber 11 to close valve 20 and shut off the supply of gas to the main burner during resetting of the safety shut-off valve. At the same time the accompanying opening of the valve 48 sets up a pilot supply of gas to the pilot burner 20 which may be lighted by a match or taper, or electrically, or otherwise as desired.

If the reset button 60 should be released before the electromagnet 51 is energized sufficiently to hold valve 48 open, this valve will close, thus shutting off bleeding or venting of gas from the first and second passage means 13, 14, and 15 and 13, 16, and 15. As a result, the gas which then passes to diaphragm chamber through passage means 13, 14, and 15 will maintain valve member 12 closed even though valve 24 should be operating to shut off the passage of gas through passage means 13, 16, and 15. When the reset button 60 is released, pin 45 moves outwardly, for example, under the action of spring 62, and automatic valve 30 is then free to open and close, for example, under the control of the thermostat 25 or other condition responsive means.

The coil 29 of the electromagnet for the automatic valve 24 is connected in circuit with the thermoelectric generator by lead conductors 70 and 71 (Figure 1) which may be of coaxial form as shown in the Oscar J. Leins patent previously identified herein, or of other suitable form. Circuit connection means is shown at 72 in Figure 2 for connection with the electromagnet for the automatic valve and with lead conductor means of coaxial form, but this may, of course, vary.

In Figure 1 one section of the lead conductor 70 is shown connected at one end to one end of coil 29 and as extending and connected at its opposite end to one of the contacts 73 of the thermostat 25 or other condition responsive device. The other section of lead conductor 70 is shown connected at one end to the other terminal 74 of the thermostat 25 or other condition responsive device, and as extending and connected at its opposite end to one side of the thermoelectric generator 22. The other lead conductor 71 connects the other end of coil 29 to the other side of the thermoelectric generator 22. One end of coil 53 of the safety shut-off valve is connected by conductor 56 to lead conductor 70, and the other end of coil 53 is connected by conductor 57 to lead conductor 71.

The connections of conductors 56 and 57 to conductors 70 and 71 are preferably disposed between the thermoelectric generator 22 and the thermostat or other control 25 so that the device 25 may operate to open and close or disable and enable the thermoelectric circuit for the automatic valve 24 without opening or closing or disabling or enabling the circuit for the coil 53 of the safety shut-off valve.

The rotatable plug 42 may be held yieldingly seated, for example, by a coiled spring 76, and preferably has not only the orifice 41, but one or more additional orifices. In Figure 2 the plug 42 is shown as having three orifices 41, 77, and 78 which are of different sizes for different gases. The orifice 41 may, for example, be for natural gas, the orifice 77 for butane, propane, or the like, and the orifice 78 for manufactured gas. The outer end of the plug 42 is shown (Figure 2)

having markings "N," "M," and "BP" and pointers which are adapted to register with a pointer 80 on the valve body part 6 to indicate which of the orifices 41, 77 or 78 is in register with the passage 40.

Orifice sizes commonly in use vary from about .020 to .024 of an inch, but this, of course, is merely illustrative and in nowise limiting. It is to be understood that the size of the orifice 23 at the pilot burner 20 may be varied to match the sizes of the orifices 41, 77 or 78, depending upon which of such orifices is to be used.

When the pilot burner 20 is extinguished safety shut-off valve 48 is in closed position shutting off the venting of gas from passage means 13, 14 and 15, and 13, 16, and 15, to the pilot burner 20. At this time the automatic valve is also de-energized and in open position for the flow of fuel, for example, through the passage means 13, 16 and 15 as shown in Figure 1 to diaphragm 11 where its energy is imposed on diaphragm 10 to close and retain the main valve 12 closed against its seat. At this time gas also flows through the passage means 13, 14, and 15, and its energy is imposed on diaphragm 10 to close and retain the main valve 12 closed against its seat 9.

With the parts in the foregoing relation the following sequence is followed to start the system:

The reset button 60 is engaged with the fingers and pressed inwardly. This opens safety shut-off valve 48 and gas passes through the conduit 19 to pilot burner 20 which is then lighted.

Upon ignition of the pilot burner 20 the flame thereof, by heating the one or more hot junctions of the thermoelectric generator 22, energizes the electromagnet 51 to hold safety shut-off valve 48 in open position. Assuming that the thermostat 25 is calling for heat, its switch is closed and the thermoelectric generator then energizes the electromagnet of the automatic valve 24 sufficiently to close and hold this valve closed. Thus there is no passage of gas to the diaphragm valve through the second passage means 13, 16, and 15, and the gas which would pass to the diaphragm valve through the first passage means 13, 14 and 15 is vented or bled to the pilot burner 20. As a result, the pressure or energy of the gas acting on the bottom of diaphragm 10 as the device is viewed in Figure 1, opens the main valve 12 for flow of fuel to main burner 1 which is ignited by the pilot burner 20.

If after the system is started the thermostat operates to position where further heat is not desired, it opens the thermoelectric circuit for the automatic valve 24. As a result this valve is deenergized and moves to open position, passing gas to diaphragm chamber 11 through the second passage means 13, 16 and 15 of the valve. This flow of gas is unrestricted, and its energy acts on diaphragm 10 to close main valve 12 and shut off the supply of fuel to the main burner 1, notwithstanding that the electromagnet 51 is energized and the safety shut-off valve 48 is open for continued burning of the pilot burner 20.

If, however, the pilot burner 20 is extinguished, the safety shut-off valve 48 closes and thereby shuts off bleeding or venting of fuel from first and second passage means 13, 14, and 15, and 13, 16, and 15. As a result the pressure or energy of the fuel on diaphragm 10 closes main valve 12 and shuts off the supply of fuel to the main burner.

With the safety shut-off valve 48 open and the 78 will cause movement of reset stem 61' for open-

pilot burner lighted, the thermostat or other condition responsive means is thus operable automatically to open and close the main valve 12 independently of the safety shut-off valve 48 which continues open as long as the pilot burner 20 is ignited and electromagnet 51 energized sufficiently to hold armature 54 in attracted position.

The latch means 63, 45, 67 assures a gas supply through second passage means 13, 16, and 15 to retain the main valve 12 closed during the resetting operation, even though the electromagnet of the automatic valve 24 should become energized.

Except for additional mechanism for assuring safe lighting, the apparatus shown diagrammatically in Figure 8 is substantially the same as that shown in Figure 1, and similar parts are therefore designated by primed reference characters corresponding to the reference characters used in Figure 1.

The mechanism for assuring safe lighting with the apparatus of Figure 8 comprises a pipe or passage 100 which communicates at 101 with the upstream side of the lower housing 6' and leads to the inlet chamber 102 of a valve housing 103 in juxtaposition to the safety shut-off valve in the conduit 19' for supplying gaseous fuel to the pilot burner 20'. A pipe or passage 104 leads from the outlet chamber 105 of valve housing 103, and opens at its opposite end, at 106, into the interior of the diaphragm chamber 11'.

A partition 107, provided with a port or opening 108, is interposed between inlet and outlet chambers 102 and 105. Port 108 is surrounded by an annular valve seat. A valve member 109 is carried by a reciprocatory reset stem 110 is adapted to seat against this valve seat to shut off the flow of gaseous fuel from the upstream side of the lower housing 6' to the diaphragm chamber 11' through pipes or passages 100 and 104, and for movement to open position when push button 111 on reset stem 110 is pressed inwardly. The valve member 109 may be returned to closed position and reset stem 110 to its outwardly projecting position when the button 111 is released by gravity or, for example, by a spring 112 or otherwise as desired. The inner end of the stem 110 is adapted to abut the reset button 60 of the safety shut-off valve 48' to actuate the valve 48' to open position and armature 54' to attracted position relative to magnet frame 52' by depressing the button 111.

The pipes or passages 100 and 104 are of relatively large diameter to provide for a large surge of gaseous fuel to diaphragm chamber 11' when valve member 109 is opened. The size of the pipes 100 and 104 and valve housing 103 may be very much larger than the orifice at 24' which may be limited by the amount of effort by a spring biased relay mechanism 29'. The safe lighting mechanism may be integral with the bonnet casting 5', but for purposes of clarity is shown diagrammatically.

When push button 111 is pressed inwardly the valve member 109 is opened to supply gas from the connection 101 into the diaphragm chamber 11' above the diaphragm. Because of the size of the valve 109 and passages 103 and 104, the diaphragm 10' will be urged instantly downwardly until valve 12' engages its seat 9' to assure that this valve is closed and held closed during resetting of the safety shut-off valve 48' to open position for ignition of the pilot burner.

Continued upward movement of the stem 110

ing valve 48' and engaging armature 54' with magnet frame 52'. After energization of the electromagnet 51' due to proper ignition of the pilot burner and heating of the thermoelectric generator 22', the button 111 may be released to place the system under control of the automatic means similar to the preceding embodiment of the invention.

The embodiment of the invention shown in the drawings is for illustrative purposes only, and it is to be expressly understood that said drawings and the accompanying specification are not to be construed as a definition of the limits or scope of the invention, reference being had to the appended claims for that purpose.

I claim:

1. In control apparatus of the class wherein there is a valve provided with a valve body having therein a diaphragm valve member operable to closed and open positions, a main fuel inlet and a main fuel outlet on one side of said valve member, a pressure chamber on the opposite side of said valve member, a first passageway connecting the inlet side of said valve with said pressure chamber, a second passageway connecting the inlet side of said valve with said pressure chamber, and a third passageway having connection with said first and second passageways for delivering gaseous fuel therefrom, the combination with said valve of a first normally closed thermoelectric device in said third passageway, a second normally open thermoelectric device in said second passageway, a thermoelectric generator connected in circuit with and common to both said first and second thermoelectric devices and adapted for holding said first thermoelectric device open and said second thermoelectric device closed when said thermoelectric generator is energized, said first thermoelectric device operating to closed position and said second thermoelectric device being adapted to operate to open position upon deenergization of said thermoelectric generator, and a rotatable plug in said first passageway having a plurality of restricted orifices of different sizes selectively positionable by rotation of said plug for the flow of gaseous fuel from the inlet side of the valve to the pressure chamber selectively through any one of said orifices.

2. In a burner control valve; in combination, a valve body, a main valve member operable to closed and open positions within the valve body, said valve body having a main fuel inlet and a main fuel outlet on one side of said valve member and a pressure chamber on the opposite side of said valve member, a first passageway connecting the inlet side of said valve with said pressure chamber, a second passageway connecting the inlet side of said valve with said pressure chamber, a third passageway having connection with said first and second passageways for delivering gaseous fuel therefrom, a first thermoelectric device in said third passageway and having an open position for delivery of fuel through said passageway and operable to closed position shutting off the delivery of fuel through said passageway, a second thermoelectric device in said second passageway and having an open position for flow of fuel to said pressure chamber through said second passageway and operable to closed position shutting off such flow of fuel through said passageway, said first passageway having a restriction therein so as to deliver to said pressure chamber insufficient gaseous fuel to cause closing of said main valve member when said first ther-

moelectric device is open but which will accumulate sufficient gaseous fuel in said pressure chamber to cause closing of said main valve member when said first thermoelectric device is closed, said second passageway passing sufficient gaseous fuel to said pressure chamber when said second thermoelectric device is open to cause closing of said main valve member when said first thermoelectric device is open, a thermoelectric generator connected in circuit with and common to both said first and second thermoelectric devices for holding said first thermoelectric device open and for closing said second thermoelectric device by energization thereof by said thermoelectric generator, said first thermoelectric device operating to closed position and said second thermoelectric device being adapted to operate to open position upon deenergization of said thermoelectric generator, reset means for resetting the first thermoelectric device to open position, and means cooperating with and actuated by said reset means for opening said second thermoelectric device and holding same open during the resetting of said first thermoelectric device to open position.

3. In a burner control valve, in combination, a valve body, a main valve member operable to closed and open positions within the valve body, said valve body having a main fuel inlet and a main fuel outlet on one side of said valve member and a pressure chamber on the opposite side of said valve member, a first passageway connecting the inlet side of said valve with said pressure chamber, a second passageway connecting the inlet side of said valve with said pressure chamber, a third passageway having connection with said first and second passageways for delivering gaseous fuel therefrom, a first thermoelectric device in said third passageway and having an open position for delivery of fuel through said third passageway and operable to closed position shutting off the delivery of fuel through said third passageway, a second thermoelectric device in said second passageway and having an open position for flow of fuel to said pressure chamber through said second passageway, said first passageway having a restriction therein so as to deliver to said pressure chamber insufficient gaseous fuel to cause closing of said main valve member when said first thermoelectric device is open but which will accumulate sufficient gaseous fuel in said pressure chamber to cause closing of said main valve member when said first thermoelectric device is closed, said second passageway passing sufficient gaseous fuel to said pressure chamber when said second thermoelectric device is open to cause closing of said main valve member when said first thermoelectric device is open, a thermoelectric generator connected in circuit with and common to both said first and second thermoelectric devices for holding said first thermoelectric device open and for closing said second thermoelectric device by energization thereof by said thermoelectric generator, said first thermoelectric device operating to closed position and said second thermoelectric device being adapted to operate to open position upon deenergization of said thermoelectric generator, reset means for resetting the first thermoelectric device to open position, a fourth passageway connecting the inlet side of the valve to the pressure chamber, and a valve disposed in said fourth passageway and operatively connected to said reset means for movement to open position by resetting oper-

11

ation of said reset means and to closed position upon completion of the resetting operation.

4. Apparatus for controlling flow of fuel to fluid fuel burning apparatus having a main burner and a pilot burner comprising, in combination, a valve body having a main fuel inlet, a main fuel outlet and a valve seat therebetween, a diaphragm carrying a main valve member having closed position cooperating with said valve seat and open position separated from said valve seat, said diaphragm being exposed on one side to energy of the fuel entering said inlet and on its other side to a pressure chamber, passage means comprising a pair of branches each connected to supply fuel from the inlet side of said valve to said pressure chamber and including a connected passage for supplying fuel to said pilot burner, a condition responsive valve in said second branch having open position for flow of fuel through said second branch and closed position shutting off said flow of fuel, a shut-off valve in said connected passage having open position for flow of fuel to said pilot burner and closed position shutting off said flow of fuel, first electromagnetic means adapted when energized to operate said condition responsive valve to closed position and to hold said condition responsive valve in said position, second electromagnetic means adapted when energized to hold said shut-off valve in open position, a thermoelectric generator adapted to be subjected to the heat of said pilot burner and electrically connected to both said first and second electromagnetic means whereby as long as said thermoelectric generator is heated by said pilot burner said shut-off valve is held in open position and said condition responsive valve is movable to closed position when the condition calls for it but upon extinguishment of said pilot burner said shut-off valve operates to closed position and said condition responsive valve operates to open position, said second branch, when said condition responsive valve is open, passing sufficient fuel to said pressure chamber to cause closing of said main valve while fuel is permitted to flow to said pilot burner and a restriction in said first branch for limiting the flow capacity of said first branch to an amount sufficient for said pilot burner when said shut-off valve is open but insufficient, when said condition responsive valve is closed, to cause closing of said main valve except when said shut-off valve is closed.

5. Apparatus according to claim 4 wherein there is reset means for resetting said shut-off valve to open position, and means under control of said reset means for opening said condition responsive valve and holding it open whereby to supply fuel to said pressure chamber through said second branch to assure closing and holding of said main valve member closed during the resetting operation of said shut-off valve to open position.

6. Apparatus according to claim 4 wherein the main valve member, the condition responsive valve, the shut-off valve and the first and second electromagnetic means are embodied as unitary parts of said valve body.

7. Apparatus according to claim 4 wherein the main valve member, the condition responsive valve, the shut-off valve, the first and second electromagnetic means, and the passage means are embodied as unitary parts of said valve body.

8. Apparatus according to claim 4 wherein the thermoelectric generator is in the form of a single thermocouple.

12

9. In control apparatus of the class described, in combination, a first valve utilizing the energy of a fluid for operation to control fluid flow through a first conduit, a shut-off valve having open position permitting fluid flow through another conduit and closed position shutting off said fluid flow, a movable armature operable to control said shut-off valve, an electromagnet for said armature, a thermoelectric generator electrically connected to said electromagnet for energizing said electromagnet, reset means for resetting said armature with respect to said electromagnet and said shut-off valve to open position, and means under control of said reset means for supplying fluid to said first valve for assuring closing and holding of said first valve closed during the resetting operation of said shut-off valve and armature.

10. In control apparatus of the class wherein there is a valve provided with a valve body having therein a diaphragm valve member operable to closed and open positions, a main fuel inlet and a main fuel outlet on one side of said valve member, a pressure chamber on the opposite side of said valve member, a first passageway connecting the inlet side of said valve with said pressure chamber, a restriction in said first passageway restricting the flow capacity of said passageway, a second passageway connecting the inlet side of said valve with said pressure chamber, and a third passageway having connection with said first and second passageways for delivering gaseous fuel therefrom, the combination with said valve of a first normally closed thermoelectric device in said third passageway, a second normally open thermoelectric device in said second passageway, a thermoelectric generator connected in circuit with and common to both said first and second thermoelectric devices and adapted for holding said first thermoelectric device open and said second thermoelectric device closed when said thermoelectric generator is energized, said first thermoelectric device operating to closed position and said second thermoelectric device being adapted to operate to open position upon deenergization of said thermoelectric generator, reset means for resetting the first thermoelectric device to open position, and means cooperating with and actuated by said reset means for opening said second thermoelectric device and holding same open during the resetting of said first thermoelectric device to open position.

11. In apparatus for controlling flow of fuel to fluid fuel burning apparatus having a main burner and a pilot burner, in combination, a valve body having a main fuel inlet, a main fuel outlet and a valve seat therebetween, a diaphragm carrying a main valve member having a closed position cooperating with said seat and an open position separated from said valve seat, said diaphragm being exposed on one side to energy of the fuel entering said inlet and on its other side to a pressure chamber having a bleed port, passage means connected to said fuel inlet, said bleed port and said pilot burner, a shut-off valve in said passage means downstream of said bleed port, said shut-off valve having electromagnetic means including a thermoelectric generator adapted to be subjected to the heat of said pilot burner and when energized to hold said shut-off valve in open position whereby fuel may flow from said inlet to said pilot burner and may also bleed off from said pressure chamber to said pilot burner 75 to effect opening of said main valve member, said

13

shut-off valve when deenergized interrupting the flow from said inlet to said pilot burner but permitting flow to said pressure chamber to effect closure of said main valve, and a condition responsive valve in said passage means, said condition responsive valve having an electromagnetic means connected in circuit with said thermoelectric generator and effective upon deenergization of its electromagnetic means by extinguishment of said pilot burner to assure more prompt closure of said main valve member.

12. In apparatus for controlling flow of fuel to fluid fuel burning apparatus having a main burner and a pilot burner, in combination, a valve body having a main fuel inlet, a main fuel outlet and a valve seat therebetween, a diaphragm carrying a main valve member having a closed position cooperating with said valve seat and an open position separated from said valve seat, said diaphragm being exposed on one side to energy of the fuel entering said inlet and on its other side to a pressure chamber, passage means including a pilot fuel supply passage connected to deliver to said pilot burner fuel from said main fuel inlet upstream of said pressure chamber and also to delivery to said pilot burner bleed fuel from said pressure chamber, a shut-off valve in said pilot fuel supply passage downstream of reception into said passage of fuel both from said main fuel inlet and from said pressure chamber, said 30 shut-off valve having electromagnetic means in-

14

cluding a thermoelectric generator adapted to be subjected to the heat of said pilot burner and when energized to hold said shut-off valve in open position and when deenergized interrupting flow of fuel through said pilot fuel supply passage to said pilot burner, and a condition responsive valve in said passage means, said condition responsive valve having electromagnetic means connected in circuit with said thermoelectric generator and effective upon deenergization of its electromagnetic means by extinguishment of said pilot burner to assure more prompt closure of said main valve member.
